UNITED STATES PATENT OFFICE.

EDWARD W. AUFDERHEIDE, OF CHICAGO, ILLINOIS.

BEADING.

1,353,885.

Specification of Letters Patent. Patented Sept. 28, 1920.

Application filed October 10, 1919. Serial No. 329,790.

To all whom it may concern:

Be it known that I, EDWARD W. AUFDERHEIDE, a citizen of the United States, and a resident of the city of Chicago, in the county of Cook and State of Illinois, have invented certain new and useful Improvements in Beading; and I do hereby declare that the following is a full, clear, and exact description of the same, reference being had to the accompanying drawings, and to the numerals of reference marked thereon, which form a part of this specification.

This invention relates to improvements in beading employed in covering the edges of the upholstered portions of furniture, automobiles and the like.

It has been proposed to make beading by driving nails or tacks along the center line of a strip of leather and then folding the edges inward to butt against each other and finally applying a cover thereto. This method is disadvantageous in many respects. In the first place, a groove appears along the center of the beading when the tacks are driven home to secure the beading in place. Further, a good round form cannot be obtained by folding once a single strip of material. Again, if the material is of sufficient thickness so that by folding once the beading has the desired dimensions, the latter is very stiff and it is difficult to curve it to correspond with the curved edge of the upholstery.

It is an object, therefore, of the present invention to provide an improved form of beading for upholstered articles.

Another object of the invention is to provide a substantially round form of beading.

A further object of the invention is to provide a more flexible form of beading.

It is also an object of the invention to provide a form of beading which will retain its round form after the tacks embedded therein have been driven home.

Other and further important objects of this invention will be apparent from the disclosures in the drawings and specification.

The invention (in a preferred form) is illustrated in the drawings and hereinafter more fully described.

According to the present invention the beading is formed from a relatively wide strip of comparatively thin material, such

as 10 oz. duck canvas. This is folded longitudinally one or more times, nails are inserted, then one edge is turned inward over the nail heads and the other edge folded inward over the first edge. Finally a suitable cover is applied. The various plies of fabric are secured together and the cover is attached to the folded fabric by a flexible form of glue or cement, such as rubber cement, to allow the completed beading to flex as desired.

In forming the beading any suitable form of apparatus may be employed, such as that illustrated diagrammatically in the accompanying drawings, in which:

Figure 1 is a diagrammatic side view of a machine for making my improved beading.

Fig. 2 is a plan view of the same.

Fig. 3 is a side view of the completed beading.

Fig. 4 is a plan view of the same.

Fig. 5 is a section on the line 5—5 of Fig. 1.

Fig. 6 is a section on the line 6—6 of Fig. 1.

Fig. 7 is a section on the line 7—7 of Fig. 1.

Fig. 8 is a section on the line 8—8 of Fig. 3.

Fig. 9 is an end view of the beading pulled apart at its end to show its construction more clearly.

As shown in the drawings:

The canvas strip or tape 1, from which the beading is to be made, is wound on a reel 2 after passing it through a bath of rubber cement or otherwise treating it to make it "tacky." From this reel the strip 1 passes over a roller 3 arranged perpendicular to the reel by which it is given a single longitudinal fold. Next the strip 1 passes around a roll 4 parallel to the reel 2, by which the folded tape is refolded to give a four-ply strip. The strip then passes under a tack delivering and applying device 5 by means of which tacks 11 are driven through the center portion of the strip at regular intervals.

Now the edges of the strip are folded inward by drawing the strip through a conical former 6, which causes the edges to overlap each other above the heads of the tacks, as shown more particularly in Fig. 8. The beading is then ready for the application

thereto of a cover 7 of leather, cloth or other material similar to that used for the upholstering of the articles to which the beading is applied.

- 5 This cover strip 7 is fed from a reel 8 around a roll 9 immediately above the beading so that the two pass together into a second conical former 10 by means of which the cover is wrapped around the beading.
- 10 The final step is the passage of the covered beading between a pair of grooved rolls 12, 13 to give the beading a uniform rounded smooth shape. The beading is then wound upon a reel 14.
- 15 I am aware that numerous details of construction may be varied through a wide range without departing from the principles of this invention, and I therefore do not purpose limiting the patent granted otherwise than necessitated by the prior art.
- 20 I claim as my invention:
1. Beading comprising a strip of fabric folded into substantially cylindrical form, having an outer cover, and tacks having their 25 points projecting beyond the beading and

their heads embedded in the folded strip of fabric.

2. Beading comprising a strip of fabric twice folded longitudinally, a line of nails passed through the center portion of the 30 double folded strip, the edges of the folded strip being turned forward to overlap each other and cover the nail heads, and an outer cover around the folded fabric.

3. A method of forming beading including folding a strip of fabric longitudinally, refolding the folded strip longitudinally, inserting nails along a line down the center of the refolded strip, then turning one edge 35 inward over the nail heads and the other 40 edge inward over the first edge and finally applying an outer cover.

In testimony whereof I have hereunto subscribed my name in the presence of two subscribing witnesses.

EDWARD W. AUFDERHEIDE.
